(57) **CLAIM**

The ornamental design for a multiplication tables educational aid set, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front elevational view of the is the first element of an multiplication tables educational aid set showing my new design;

FIG. 2 is the second element thereof;

FIG. 3 is the third element thereof;

FIG. 4 is the forth element thereof;

FIG. 5 is the fifth element thereof;

FIG. 6 is the sixth element thereof;

FIG. 7 is the seventh element thereof;

FIG. 8 is the eighth element thereof;

FIG. 9 is the ninth element thereof; and,

FIG. 10 is the tenth element thereof.

The colors shown in FIGS. 1-10 constitute part of the claimed design.

Features and views not shown in the drawings form no part of the claimed design.

The broken lines in FIGS. 1-10 represent the boundaries of each element of the set and form no part of the claimed design.
